FILAMENTARY ELECTRODE STRUCTURE FOR ELECTRON DISCHARGE DEVICES

George E. Carter, Jr., Danvers, Mass., assignor to Bomac Laboratories Inc., Beverly, Mass., a corporation of Massachusetts

Filed May 17, 1954, Ser. No. 430,197

4 Claims. (Cl. 313—275)

The present invention relates to an electrode structure for electron discharge devices and more particularly to a non-microphonic filamentary cathode of ruggedized construction for thermionic tubes.

Recent military developments have shown the increasing need for thermionic tubes capable of withstanding acceleration shocks up to 100,000 gravities and be able to perform satisfactorily. In prior art devices, filamentary cathodes are commonly tensioned to prevent buckling when heated. This tensioning results in the filament having a natural resonant period which renders it unsuitable for use in devices subjected to conditions of severe accelerations, shocks and vibrations.

A further disadvantage of prior art filaments is the phenomenon referred to in the art as microphonism and noise. Since the electrode spacings are critical and vital for the performance of the device, any vibrations will cause variations in the current flow from the filament to other elements. These variations may be noted in output as viewed on an oscilloscope through a suitable test circuit, and are predominantly the result of harmonic or random vibrations of the tensioned filament.

To overcome the disadvantages mentioned, the invention discloses a novel filamentary cathode structure capable of performing in thermionic devices subjected to severe accelerations, shocks and vibrations and requiring rapid warm-up times, without distortion, breakage or generation of microphonics.

It is an object of the present invention to provide a novel electrode structure in thermionic tubes capable of withstanding extreme conditions of shock, vibration and high accelerations.

A still further object is to provide a novel ruggedized filamentary cathode having rapid warm-up times.

Another object is the provision of a novel filamentary cathode for thermionic tubes that is non-microphonic.

A feature of the invention relates to a filamentary cathode spirally and helically wound on a rigid supporting member thus eliminating the use of any tensioning devices. While the prior art discloses filamentary cathodes wound on a refractory mandrel such structure cannot be employed in devices subjected to extreme accelerations, shocks and vibrations because of the inherent brittleness of the mandrel. I have discovered, however, that a sheath or sleeve of a conductive metal may be fitted over a core of a material of low thermal conductivity and a metallic filament wound over a portion of the sheath will provide an extremely rigid filament structure.

Further, the metallic sheath provides not only the desired rigidity, but an efficient means for conducting current to the filament cathode.

The disclosed structure also provides a ruggedized structure having no natural resonant frequencies.

The objects, features and advantages will be more readily appreciated after consideration of the following detailed specification and accompanying drawings in which:

2

Figure 1 is an enlarged perspective view of an embodiment of the invention with a portion of the envelope and components broken away;

5 Figure 2 is a detailed cross sectional view along the line 2—2 in Figure 1;

Figure 3 is an exploded view showing the relationship of the components of the filamentary cathode of my invention; and

10 Figure 4 is an enlarged perspective view of the assembled cathode of the invention; and

Figure 5 is a detailed cross sectional view of the embodiment of the invention.

Referring to Figure 1 and Figure 2, the embodiment of the invention resides in a thermionic tube 1 constructed generally according to the disclosure and claims of co-pending application of Richard S. Briggs and George E. Carter, Jr., Serial No. 430,196 filed May 17, 1954. The envelope consists of a cylindrical main body member 2 with end members 3 and 4 hermetically sealed thereto by brazing or other sealing methods. The assembled envelope defines a central passageway in which the electrode structure is positioned concentrically around a common axis. Flanged eyelets 5 and 6 are joined coaxially at the ends of members 3 and 4 by means of glass to metal seals 7 and 8. Tubular members 9 and 10 are joined in a like manner to the flanged eyelets by glass to metal seals 11 and 12 to enclose the ends of the envelope.

30 The electrode structure of the embodiment comprises a metallic plate insert 13 of a generally rectangular shape affixed to the inside surface of the body member 2. The insert serves as the anode electrode and external circuit connection means may be attached to this body member. A grid electrode 14 is supported at one end 35 by a sleeve 15 mounted at the inner end of eyelet 5 with suitable indentations 16 to receive grid side rods 17. Grid 14 consists of metallic side rods 17 with a plurality of turns 18 of a suitable wire helically wound and fixed thereon as shown. The opposite end of the grid is supported by an apertured insulating spacer 19 positioned and supported within envelope and member 4. The external circuit connections may be made to eyelet 5.

40 The assembled envelope with plate insert and grid electrode may be hydrogen fired to clean the components as well as braze the main body member 2 and end members 3 and 4. Such processing prior to the mounting of the cathode electrode eliminates the dangers of any contamination of this electrode particularly when emissive coatings containing metallic oxides are employed.

45 A filamentary cathode embodying the teachings of the invention is supported axially within the central passageway by tubular members 9 and 10. The construction of this electrode will now be described by referring to Figures 3 and 4.

50 A pair of tubular metallic sheaths 20 and 21 of a conductive metal, such as nickel or the alloy "Kovar" which is composed of nickel, iron and cobalt, are provided with a rolled or peened section 22 intermediate to the ends thereof. Supported with one end in each sheath is a post 23 of a low thermal conductivity material such as Alundum with the ends of said post in contiguous relationship with section 22. Other means for preventing longitudinal movement of the post may be employed. The sections 22 have been observed to act not only as stop means, but also act as expansion joints to still rigidly support post 23 when the cathode is heated.

55 To prevent heat conduction from the filament to the supporting member, a heat insulating barrier is desirably established. This may be accomplished in several ways, such as the application of a coating of a rough and porous heat insulating material applied to the post at an intermediate portion thereof to form a sleeve abutting

the metallic sheaths 20 and 21. An alternative method may be to slide a sleeve of the desired rough and porous insulating material over the post before assembling the metallic sheaths over the ends of said post.

I have found that a coating of a rough and porous refractory material on the post will prevent excessive heat conduction from the filament to the post.

In the illustrative embodiment, I, therefore, provide on the exposed surface of the post 23 when assembled between sheaths 20 and 21, a sleeve 24 of a low conductivity refractory material. Sleeve 24 consists of essentially a 97% mixture of alumina and silica with traces of titanium, calcium, iron and magnesium oxides. This material was ground and powdered to a particle size of 300 mesh or over and was mixed with a suitable binding agent. The mixture may be applied by spraying, dipping or painting the desired surface. After applying, the coating is allowed to dry to form a sleeve having approximately the same diameter as the abutting sheaths.

A thin metallic filament 25 is spirally and helically wound on the sheaths 20 and 21 and coated post 23, so as to provide the maximum emitting area over a short length. Several overturns of the filament wire are provided on sheaths 20 and 21 with the ends affixed to said sheaths to provide efficient contact as at 26. Additional points for fixing the filament on the sheaths may be selected if desired.

Following the winding and fixing of the filament on the rigid structure an emissive coating 27 may be applied by conventional techniques. The coating will be applied to the filament turns as well as the areas of the exposed sleeve between said turns. It has been observed that the coating in this area will outgas satisfactorily during processing. In the illustrative embodiment a filament structure comprising a coated filament has been described, however, similar results will be attained with the use of a filament suitably impregnated with an electron emissive material.

The cathode assembly is mounted axially within the central passageway and is rigidly supported by tubular members 9 and 10. Electrical connection means for this electrode may be made by means of said members 9 and 10. The ends of the tubular members are vacuum sealed as at 28 and 29. It is desirable to allow the sealing material to flow in the spaces between the cathode sleeve and supporting members to further ruggedize and fix the cathode assembly.

Degassing of the tube may be accomplished by means of a getter bar 30 mounted on tabs 31 and 32 in space 33 between glass to metal seal 8 and insulating spacer 19. Tabs 31 and 32 may be conductively connected to eyelet 6 and envelope end member 4 respectively, to provide electrical continuity for vaporizing of the gettering material.

Exhaust tubulation 34 extends into a passageway provided in end member 4. After evacuating the assembled tube and flashing of the getter, the tubulation is tipped and sealed.

Figures 4 and 5 illustrate further the novel features of the filamentary cathode of the invention. While I have provided a passageway 35 through the post 23, a solid post will produce satisfactory results. The low thermal conductivity characteristics of the post 23 are further enhanced by the sleeve of refractory coating 24 which, in turn, supports the filament turns. The rough and porous surface of the coating in contact with the filament reduces the contact area and heat conduction.

The pitch of the filament turns tends to prevent slipping and over-riding when the filament is heated and subjected to severe accelerations, shocks and vibrations.

Filamentary cathodes constructed according to the teachings of the invention have reached the full emitting state in less than three tenths of a second after application of the heating voltage. With the structure described, the filamentary cathode has no natural resonances comparable with those of conventional stretched wire filaments and creates no variations in the output of the illustrative tube when employed in an oscillator circuit. Thermionic tubes with the cathode of the invention have been adapted with proper circuitry to perform as amplifiers, rectifiers or detectors.

Further, the filamentary cathode of the invention facilitates minaturization as well as ruggedizing of thermionic tubes in that the elimination of prior art filament suspension and support structure has resulted in tubes having an overall length under 1.25 inches. Ease of fabrication as well as simplicity of construction makes it possible for devices of the character described to be produced with modern high speed production techniques.

While an illustrative embodiment of the invention has been disclosed various modifications will occur to those skilled in the art. Therefore, it is my intention to cover in the appended claims such modifications or variations as fall within the spirit and scope of the invention.

What is claimed is:

1. A filamentary electrode structure comprising a core of a low thermal conductivity material, a sleeve of a rough surfaced heat insulating material mounted upon said core at an intermediate portion thereof, a pair of metal sheaths fitted over said core in abutting relation to said sleeve, a filament wound helically upon said sheaths and sleeve, and a layer of electron emissive material deposited upon said filament and the surface of said sleeve.

2. A filamentary electrode structure comprising a cylindrical core of a low thermal conductivity material, a sleeve of a rough surfaced heat insulating material mounted upon said core at an intermediate portion thereof, a pair of tubular metal sheaths fitted over said core in abutting relation to said sleeve, a flat filamentary metal ribbon wound helically upon said sheaths and extending across said sleeve, and a layer of electron emissive material deposited upon said ribbon and the surface of said sleeve.

3. A filamentary electrode structure comprising a cylindrical core of a low thermal conductivity material, a sleeve of a rough and porous heat insulating material mounted upon said core at an intermediate portion thereof, a pair of tubular metallic sheaths fitted over said core, said sheaths having approximately the same diameter as said sleeve, a plurality of turns of a thermionic filament helically wound upon said sleeve and a portion of said metallic sheaths, said filament being supported by and in intimate contact with said sheaths.

4. Ruggedized electrode structure for electron discharge devices comprising a core of a low thermal conductivity material, a sleeve of a refractory material mounted on an intermediate portion of said core, a pair of rigid metallic members fitted on said core and in abutting relation with said sleeve, and a metal filament wound helically upon said metallic members and sleeve, said metallic members serving to reinforce said core, support said filament and conduct current thereto.
